CLAIM

We claim the ornamental design for a headphone, as shown and described.

DESCRIPTION

FIG. 1 is a perspective view of a headphone; FIG. 2 is a front elevational view of the headphone; FIG. 3 is a rear elevational view of the headphone; FIG. 4 is a top plan view of the headphone; FIG. 5 is a bottom plan view of the headphone; FIG. 6 is a left side elevational view of the headphone; FIG. 7 is a right side elevational view of the headphone; FIG. 8 is a right side perspective view of the headphone of FIG. 2 as seen from arrow 8 of FIG. 2; and, FIG. 9 is an enlarged partial end view of the headphone taken along line 9-9 of FIG. 8.

Portions of the drawings shown in broken lines form no part of the claimed design.

1 Claim, 9 Drawing Sheets
